US0D1083516S

(12) United States Design Patent (10) Patent No.: US D1,083,516 S
(45) Date of Patent:  Jul. 15, 2025

(54) DRINKING GLASS

(71) Applicant: TURKIYE SISE VE CAM FABRIKALARI ANONIM SIRKETI, Istanbul (TR)

(72) Inventors: Umut Sinan Karaca, Istanbul (TR); Basak Emirhanoglu, Istanbul (TR)

(73) Assignee: TURKIYE SISE VE CAM FABRIKALARI ANONIM SIRKETI, Istanbul (TR)

() Term: 15 Years

(21) Appl. No.: 35/519,618

(22) Filed: Nov. 9, 2023

(80) Hague Agreement Data

Int. Filing Date: Nov. 9, 2023

Int. Reg. No.: DM/234121

Int. Reg. Date: Nov. 9, 2023

Int. Reg. Pub. Date: Jan. 5, 2024

(30) Foreign Application Priority Data

Jun. 15, 2023 (TR) 2023/006052

(51) LOC (15) Cl. 07-01

(52) U.S. Cl.

USPC D7/531

(58) Field of Classification Search
